(57) **CLAIM**

The ornamental design for a light covering, as shown and described.

DESCRIPTION

FIG. 1 is a perspective view of a light covering showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed broken lines shown in the drawings are included for the purpose of illustrating elements of the light covering that form no part of the claimed design. The dot-dash-dot lines represent surface contours and not surface ornamentation.
